UNITED STATES PATENT OFFICE

ALBERT S. RIVIERE, OF CHICAGO, ILLINOIS, ASSIGNOR TO UNION SPECIAL MACHINE COMPANY, OF CHICAGO, ILLINOIS, A CORPORATION OF ILLINOIS

PRESSER FOOT FOR SEWING MACHINES

Application filed July 27, 1929. Serial No. 381,494.

This invention relates to new and useful improvements in a presser foot for sewing machines, and more particularly to a presser foot for guiding the upturned edge portions of fabric sections for trimming, and which is provided with means for turning down the trimmed portions in flat overlapped relation for stitching.

An object of the invention is to provide independent yielding devices for turning down the lapped edge portions of the fabric sections, which yielding sections are independently mounted and which are capable of moving beneath the plane of the under face of the presser foot so as to firmly hold said lapped sections against the work support during the raising of the presser foot by a cross seam passing beneath the same.

In the drawings:

Fig. 1 is a top plan view of the presser foot embodying the invention.

Fig. 2 is a bottom plan view of the same.

Fig. 3 is a sectional view on the line 3—3 of Fig. 1.

Fig. 4 is a sectional view on the line 4—4 of Fig. 1.

Fig. 5 is a sectional view on the line 5—5 of Fig. 1.

The invention is directed to a presser foot for sewing machines producing a flat seam. Associated with the presser foot are horizontally disposed trimming devices. The presser foot is provided with a channel for directing the upturned edge portions of fabric sections to the trimming devices and also with means for turning down the trimmed edge portions into flat lapped position for stitching. The presser foot is also provided with yielding members in the under faces of the foot sections at each side of the channel. The edge portions of the fabric sections after they are trimmed engage respectively devices which forcibly turn said sections down into flat position. The edge portion which is to form the underlap is turned down first and then the edge portion which is to form the upper lap is turned down onto the same. These devices which forcibly turn down the edge portions are disposed at the inner end of the channel which guides

the upturned edge portions to the trimming devices. They are also located in front of the needle opening, and consequently, operate upon the fabric between the time when said edge portions are trimmed and when the 55 edge portions are joined by the stitches.

These members are yieldingly mounted and the member operating upon the underlap section is capable of moving downward to a position beneath the lower face of the 60 presser foot so that when the presser foot is raised by a cross seam entering beneath the forward end thereof this yielding device will remain in contact with the fabric section and hold the fabric section firmly down on the throat plate.

Referring more in detail to the drawings, the presser foot which embodies the invention includes a shank portion 1 which is adapted to be attached to the ordinary presser bar. This shank portion has formed integral therewith rigid fabric engaging sections 2 and 3. The rigid sections are spaced apart so as to form a guiding channel 4 through which the upturned edge portions of the 70 fabric sections are led to the trimming devices. The trimming devices include a stationary trimming member 5 mounted on the rigid section 2 of the presser foot, and a movable trimming member 6 which cooperates with the stationary trimming member.

These trimming devices are so disposed relative to the channel 4 that the upturned edge portions of the fabric sections are trimmed, thus preparing the fabric sections 85 for lapping and stitching.

The presser foot is provided with a needle opening 7 which is in line with the channel 4. On the under side of the fabric engaging section 2 of the presser foot is a non-flexible yielding member 8. Said member is carried by posts 9, 9. Fig. 4 is a section through the foot at one of these posts. A spring 10 surrounds the post and bearing against the foot section 2 and also the member 8 normally forces said member downward so that the lower face thereof is beneath the lower face of the presser foot section 2. A pin 11 limits the downward movement of the post.

As noted there are two posts which are similar in construction.

The other presser foot section 3 is provided with a recess in its under face in which is located a non-flexible yielding member 12 carried by posts 13, 13 which are similar in construction to those described above. These non-flexible yielding members in the under faces of the presser foot sections are for the purpose of taking care of uneven thicknesses in the fabric sections being stitched. They form no part of the present invention per se, but are the invention of Alfred T. Chidley and are shown described and claimed in his application Serial No. 367,937, filed June 3, 1929.

The present invention is directed to the construction and mounting of the devices for turning down the edge portions of the fabric sections into lapped relation for stitching. At the inner end of the channel there is a turning down device 14. This turning down device 14 has a curved under face 15 leading to a flat portion which engages the fabric section after it is turned down. This device 14 is made of spring metal and is provided with a relatively long shank 16 which is secured to the presser foot section 2 by means of a screw 17. The shank is formed integral with an upwardly projecting portion 16a which is likewise integral with the active portion of the turning down device 14. The length of the shank 16a is such that when the presser foot is raised, the under face of the device 14 can move to a position beneath the under face of the rigid portion of the presser foot. If, during the stitching of the fabric sections, a cross seam passes beneath the front end of the presser foot, it will raise the presser foot to an extent depending upon the thickness of the cross seam. If this turning down device 14 were rigid with the presser foot it would also be lifted with the presser foot and would thus be lifted off from the fabric section in advance of the cross seam. This would not only release the pressure on the fabric section as turned down but it would also release the force being applied to the turning down of the underneath fabric section and likewise raise the upper lapped portion of the fabric section just passing over the same.

The extent to which the yielding device 14 can move downward beneath the lower face of the rigid portion of the presser foot is sufficient to take care of any ordinary cross seam so that when the presser foot is raised this device 14 will remain in contact with the fabric directly in rear of the trimming device and in front of the needle opening. The device 14, as is clear from the drawings, is at the inner end of the channel and engages the fabric section after it is trimmed to turn it down and before it is stitched because the turning down of the fabric section must be

accomplished before it is stitched. The other edge of the fabric section is turned to flat lapped position by a turning down device 18. This turning down device 18 is carried by a shank 19 through which a screw 20 passes. Surrounding the screw 20 and bearing on the shank 19 is a spring 21. This allows the turning down device 18 to yield upwardly.

The stitch fingers 22, 22 are carried by this yielding device. As the cross seam is passing through the turning down device, it can lift this upper turning down member so that not only is the foot raised to permit the cross seam to pass the stitching device, but the turning down devices are separated so as to give ample space for the cross seam to pass.

From the above it will be apparent that the yielding mounting of these devices which turn down the two fabric sections into lapped relation provides a much more efficient control of the fabric sections, particularly when cross seams are passing under and across the under face of the presser foot.

It will be obvious that minor changes in the details of construction may be made without departing from the spirit of the invention as set forth in the appended claims.

Having fully described my invention, what I claim as new and desire to secure by Letters Patent, is:—

1. A presser foot for sewing machines including in combination a foot portion having a needle opening therethrough, a guiding channel extending from the front end of the foot portion longitudinally thereof for directing the upturned edge portions of the fabric sections, said presser foot having devices for turning down the edge portions into overlapped relation with each other, and means for yieldingly supporting said device operating on the under lapped fabric section on said foot portion whereby said device is capable of remaining in contact with the fabric when the presser foot is raised by a passing cross seam.

2. A presser foot for sewing machines including in combination a foot portion having a needle opening therethrough, a guiding channel extending from the front end of the foot portion longitudinally thereof for directing the upturned edge portions of the fabric sections, said presser foot having devices for turning down the edge portions into overlapped relation with each other, and independent yielding means for supporting each of said devices on said foot portion whereby said device engaging the under lapped section may remain in contact therewith when the presser foot is raised by a passing cross seam and whereby said device engaging the upper lapped section may yield relative to the device engaging the under lapped section to permit a cross seam to pass between said devices.

3. A presser foot for sewing machines including in combination a foot portion having a needle opening therethrough, a guiding channel extending from the front end of the foot portion longitudinally thereof for directing the upturned edge portions of the fabric sections, said presser foot having devices for turning down the edge portions into overlapped relation with each other, independent yielding means for supporting each of said devices on said foot portion whereby said device engaging the under lapped section may remain in contact therewith when the presser foot is raised by a passing cross seam and whereby said device engaging the upper lapped section may yield relative to the device engaging the under lapped section to permit a cross seam to pass between said devices, and stitch fingers carried by said device engaging the upper lapped fabric section.

4. A presser foot for sewing machines including in combination a foot portion having a needle opening therethrough, a guiding channel extending from the front end of the foot portion longitudinally thereof for directing the upturned edge portions of the fabric sections, said presser foot having devices for turning said fabric sections into overlapped relation with each other, said device engaging the under lapped fabric section having a lower flat face adapted to engage the turned down portion of the fabric section and an inclined face for turning down said section, and yielding means for supporting said device on said foot portion whereby the flat portion can move to a position beneath the under face of the foot portion of the presser foot.

40 In testimony whereof, I affix my signature.
ALBERT S. RIVIÈRE.
